UNITED STATES PATENT OFFICE.

WILFRED STAFFORD, OF LONDON, ENGLAND, ASSIGNOR TO THE OLIVER TYPEWRITER CO. LTD., OF LONDON, ENGLAND, A CORPORATION OF GREAT BRITAIN.

TAPE-COPY-HOLDER ATTACHMENT FOR TYPE-WRITERS.

1,104,568.

Specification of Letters Patent. Patented July 21, 1914.

Application filed October 4, 1913. Serial No. 793,425.

To all whom it may concern:

Be it known that I, WILFRED STAFFORD, a subject of the King of Great Britain, residing at London, England, have invented 5 new and useful Improvements in Tape-Copy-Holder Attachments for Type-Writers, of which the following is a specification.

This invention relates to a tape holder attachment for typewriters, of the kind where- 10 in the tape is drawn across the typewriter in view of the transcriber by means of a spring motor when the transcriber presses a key which controls the operation of said spring motor.

15 In my improved attachment, the key is ar- ranged to control the spring motor by means of an escapement comprising two detent teeth or arms one of which engages with projections arranged on the periphery of a 20 drum on one of the arbors of the spring motor, and prevents rotation of the motor so long as the releasing key is not depressed, and the other of which engages with the said 25 projections when the key is depressed. More- over, by allowing the said arms to abut against the periphery of the drum, large 30 wearing surfaces can be obtained and the durability of the mechanism increased.

By my invention I insure that not more 35 than the desired length of tape shall be fed along the guide at each depression of the controlling key, whether such depression is long or short.

In the accompanying drawings, I have 40 shown how my said invention may be conveniently and advantageously carried into practice.

In this drawing:—Figure 1 is a perspective view of a typewriter having my invention applied thereto. Fig. 2 is a plan of my 45 improved attachment shown separately. Fig. 3 is a vertical section on the line α , α , Fig. 2, and Fig. 4 a rear elevation, both drawn to an enlarged scale, showing the spring-motor and connected parts separately.

a is the frame of a typewriter and b the tape-guide or holder, in which the tape rests during transcription. c is a casing bolted to the frame a . d is the tape-feed roller 50 fixed to a shaft e rotatably mounted in the upper part of the casing c . This shaft e also bears a pinion f gearing with a spur-wheel g rotatably mounted in the casing c . These 55 parts together with an idle roller h drawn by springs j on to the roller d , are substan-

tially the same as those described in the specification of British Letters Patent No. 15805 of 1911 of which I am one of the patentees.

In order to drive the gear wheel g and 60 connected parts automatically, the said wheel has fixed thereto a pinion k which gears with a spur-wheel m rotatably mounted on a shaft m' . This shaft is rotatably mounted in the casing c and is connected to the wheel 65 m by means of a spring o arranged in a spring-barrel p mounted on said wheel. The shaft m' bears at the front end a handle q , whereby it may be turned to wind up the spring o and at the rear end a ratchet-wheel 70 r which engages with a pawl s to prevent it from being turned back by the spring o . The spring barrel p bears on its periphery a series of projections t , t which are spaced 75 at equal distances apart so as to form an escapement-wheel and are adapted to engage with a pair of detent-arms u , v , on a rock- shaft w which is pivotally mounted in the casing c . The rear end of this rock-shaft ex- 80 tends to the exterior, where it is provided with a lever arm x , which is coupled by an adjustable link y to one of the upper ends of a T-lever z pivoted at 1 to the bracket 2 supporting the casing e . The other upper end of the T-lever engages with a link or coupling 85 rod 3 actuated by one of the keys of the typewriter in any suitable known manner. When the parts are at rest, the spring barrel p and connected parts are retained by the 90 engagement of the detent arm u with one of the projections t . When however the T- lever z is rocked by the depression of the cor- 95 responding key, the said projection t is re- leased by the detent arm u , whereupon it passes beneath said arm and comes into en- gagement with the other detent arm v which now lies in its path. On the release of the 100 key, the arm v rises and releases the projec- 105 tion t in engagement therewith, while the arm u moves back into the path of the pro- jec-

110
 a is the frame of a typewriter and b the tape-guide or holder, in which the tape rests during transcription. c is a casing bolted to the frame a . d is the tape-feed roller 50 fixed to a shaft e rotatably mounted in the upper part of the casing c . This shaft e also bears a pinion f gearing with a spur-wheel g rotatably mounted in the casing c . These 55 parts together with an idle roller h drawn by springs j on to the roller d , are substan-

tions t , t , there is no risk of the wheel m rotating through a greater angle than that corresponding to the pitch of the projections t , t , for each actuation of the lever z .

What I claim is:

A tape copy holder attachment for type-writing machines, said attachment comprising a copy holder, a spring motor, a driving roller actuated by said spring motor for driving the tape along said copy holder, a key, a drum fixed to one of the wheels of the spring motor, projections on the periphery

of said drum, a rock-shaft arranged adjacent to said drum, oppositely arranged detent arms mounted on said rock-shaft and adapted to move into and out of engagement with the periphery of said drum and with said projections, and means for operatively connecting said rock-shaft and said key. 15

WILFRED STAFFORD.
